UNITED STATES PATENT OFFICE

WILFRID BRIÈRE, OF MONTREAL, QUEBEC, CANADA

HOLDER AND EJECTOR FOR CIGARETTES AND CIGARS

Application filed September 10, 1931. Serial No. 562,123.

In the use of holders or mouthpieces for cigarettes and cigars, it is often found that the unconsumed end or stub is too short to be grasped and pulled out, or that the smoker prefers not to touch the stub with his fingers. In order to meet this condition, the present invention provides an ejector for discharging the stub without requiring that the stub be at all handled.

Accordingly, there is provided a slidable member on the wall of the cavity of the mouthpiece or holder, and this member has a portion lying transversely in the cavity to engage the seated end of the cigarette or cigar. To eject a stub, it is only necessary to slide this member outwardly by means of a suitable finger piece provided thereon.

The invention is fully disclosed by way of example in the following description and in the accompanying drawing in which

Figure 1 is a side elevation of the device; Figure 2 is a longitudinal section thereof;

Figure 3 is a similar section in another position;

Figure 4 is a plan view;

Figure 5 is a section on the line 5—5 of Figure 3;

Figure 6 is a section on the line 6—6 of Figure 2; and

Figure 7 is a developed view of the ejector.

Reference to these views will now be made by use of like characters which are employed to designate corresponding parts throughout.

In the several figures is illustrated a mouth piece or holder 1 for cigarette or cigar. This device has the usual bore or smoke passage 2 terminating in a cavity 3 for receiving an end of a cigarette.

In order to accommodate the ejector which constitutes the novel feature of this invention, the wall 4 around the cavity 3 is formed with a pair of longitudinal grooves 5 and 6 respectively in the outer and inner surfaces thereof. The grooves are preferably dovetailed for a purpose which will presently appear.

The ejector proper comprises a blank 7 of sheet metal bent upon itself at 8 to form two laps 9 and 10. These laps are slidably received in the grooves 5 and 6 respectively.

The lap 9 has a longitudinal slot 11 in which is received a headed stud 12 anchored in the wall 4. The stud 12, in conjunction with the dovetailed shape of the grooves 5 and 6, prevents the ejector from dropping out of the grooves although permitting slidability. The stud, moreover, prevents the ejector from being pulled entirely off the mouthpiece.

The inner lap 10 has its free end bent at a right angle to form a follower 13 lying transversely in the cavity 3 as shown more clearly in Figures 3 and 5. This member is adapted to abut the end of a cigarette and is formed with an aperture 14 in line with the passage 2 to permit the smoke to be drawn from the cigarette into the passage.

The free end of the outer lap 9 is bent outwardly to form a finger piece 15 by which the ejector may be grasped in adjusting from one position to another. The blank 7 may be notched at 16 in the edges to facilitate making the bends heretofore described.

In the use of the device, the ejector is retracted to the position shown in Figure 2 prior to inserting a cigarette, and is retained in this position until the cigarette is to be removed. If the unconsumed end of the cigarette is too short to be grasped or if the smoker prefers not to touch it, the ejector is advanced to the position shown in Figure 3 by merely pushing the tab 15, whereupon the stub is discharged from the holder.

Although a specific embodiment of the invention has been illustrated and described, it will be understood that various alterations in the details of construction may be made without departing from the scope as indicated by the appended claims.

What I claim is:

1. A holder and ejector for cigarettes or cigars comprising a mouthpiece having a passage and a cavity, a metal strip bent upon itself and slidably mounted on the wall of said cavity in engagement with the inner and outer surfaces thereof, the outer portion of said strip having a slot, a headed stud passed through said slot and into said holder, said strip having a portion lying transversely in said cavity.

2. A holder and ejector for cigarettes or

cigars comprising a mouthpiece having a passage and a cavity, a metal strip bent upon itself and slidably mounted on the wall of said cavity in engagement with the inner and outer surfaces thereof, the outer portion of 5 said strip having a slot, a headed stud passed through said slot and into said holder, said strip having a portion lying transversely in said cavity, said portion bridging said cavity and having an aperture in line with said passage.

10 In witness whereof I have hereunto set my hand.

WILFRID BRIÈRE.
